UNITED STATES PATENT OFFICE.

FRANK W. THOMAS, OF WILLIAMSPORT, PENNSYLVANIA.

SPOUT-HANGER.

972,291.

Specification of Letters Patent. Patented Oct. 11, 1910.

Application filed September 14, 1909. Serial No. 517,715.

To all whom it may concern:

Be it known that I, FRANK W. THOMAS, a citizen of the United States of America, residing at Williamsport, in the county of Lycoming and State of Pennsylvania, have invented certain new and useful Improvements in Spout-Hangers, of which the following is a specification, reference being had therein to the accompanying drawing.

10 This invention relates to eavestrough hangers, and the principal object of the same is to provide means whereby the hangers may be adjusted for roofs of various pitch and also means whereby the trough 15 support may be vertically adjusted.

In carrying out the objects of the invention generally stated above it is contemplated employing a main bar or body to which the roof engaging member has a pivotal connection so that the same may be adjusted in accordance with the pitch of a roof, means being provided whereby said member may be locked in adjusted position, and a trough support having a detachable vertically adjustable engagement with said body.

It will be understood, of course, that the essential features of the invention involved are necessarily susceptible of changes of details and structural arrangements, one preferred and practical embodiment of which is shown in the accompanying drawing wherein—

35 Figure 1 is a side view of the improved eavestrough hanger. Fig. 2 is a detail perspective view of the body of the hanger. Fig. 3 is a similar view of the roof engaging member. Fig. 4 is another similar view showing, in detail, the trough support. Fig. 40 5 is a horizontal sectional view taken on the line 5—5 Fig. 2.

Referring to said drawings by numerals, (1) designates the flat elongated body of the improved eaves trough hanger, one side of which is provided with longitudinal edge flanges (2) which provide a guide way extending the major portion of the length of said body. The body is also provided with a plurality of regularly spaced apart transverse slots (3). The upper end of said body (1) is provided with an outwardly and upwardly curved pivot hook (4), and below said hook (4), the body (1) is provided with a laterally projecting lip (5) having an opening (6) through it.

The trough support is composed of an

outwardly curved arm (7) shaped to conform to the contour of an eavestrough, the inner end (8) of said arm being provided with a hook (9) for engagement with one edge of the trough, said inner end (8) being widened and provided with a vertically arranged guiding lug (10) from which a lip (11) projects, said lip having an opening (12) formed through it. The guiding lug 65 (10) is adapted to be fitted within the guideway of the member (1) and the lip (11) passes through one end of the slots (3) and detachably retained therein by means of a pin (13) which is passed through the opening (12) of said lip (11). 70

A roof engaging member (14) has a flattened angular head (15), said head (15) having a pivot opening (16) at its inner portion, and having its outer edge enlarged and rounded on an arc of a circle and provided with a guide slot (17) which is adjacent to and parallel with the said outer edge. Grooves (18) radiate from the outer edge of said head (15), the grooves being broken by said guide slot (17). The body of the member (14) has openings (19) by means of which it may be fastened to a roof. 75 80

In assembling the parts of the invention, 85
the member (14) has its body fastened to a
roof with its head (15) projecting outward.
The pivot hook (4) of the body (1) is
passed through the opening (16) of the
head (15) and the lip (5) is passed through
the guide slot (17) and fastened therein by
means of a pin (20), which is passed
through the opening (6) of said lip (5)
and rests within one of the grooves (18). 90
The lug (8) of the trough support is then
placed within the guideway of the body (1)
with its lip (11) projected through one of
the slots (3) and fastened therein by means
of the pin (13). The pins (13) and (20) 95
are preferably wedge shaped so that they
may be tightened within these lips, yet
readily withdrawn when adjustments are to
be made, or when the improved hanger is
to be disassembled. 100

It will be seen from the foregoing that the roof member (14) is a stationary member, and that the body (1) may be adjusted angularly thereon by means of the pivotal connection and be locked in the desired adjusted position by means of the lip (13), guide slot (17), pin (20) and grooves (18). Also that the trough support may be ad-

justed longitudinally of the body (1) by means of the slot (3) and lip (5) and locked in the desired position by the pin (13). As will be obvious, the guideway of the body (1) and the lug (8) of the trough support coöperate to prevent lateral play of the trough support relative to the body (1).

What I claim as my invention is:

An eavestrough hanger comprising a roof 10 engaging member provided with an angular head, said head being provided with a pivot opening, a guide slot, and radiating grooves, a body having a pivot hook for engagement with said pivot opening and a lip for en-

gagement with said slot, whereby said body 15 may be adjusted angularly of said roof-engaging member, a pin for said lip adapted to be selectively seated in any of said grooves to lock the body in an adjusted position, and a trough support adjustably connected with said body. 20

In testimony whereof I hereunto affix my signature in presence of two witnesses.

FRANK W. THOMAS.
